UNITED STATES PATENT OFFICE.

HOBART W. McNEILL, OF OSKALOOSA, IOWA.

CABLE-RAILWAY CAR.

SPECIFICATION forming part of Letters Patent No. 371,694, dated October 18, 1887.

Application filed March 1, 1887. Serial No. 229,354. (No model.)

To all whom it may concern:

Be it known that I, HOBART W. McNEILL, a citizen of the United States, residing at Oskaloosa, in the county of Nahaska, State of 5 Iowa, have invented certain new and useful Improvements in Cable-Railway Cars, of which I do declare the following to be a full, clear, and exact description, reference being had to the accompanying drawings, forming part of 10 this specification.

My present invention has relation more particularly to cable-railway cars of that system wherein the propulsion of the car is effected by means of a traveling cable provided 15 throughout its length with suitable buttons or stops adapted to engage with the arms of a sprocket-wheel projecting from beneath the car into the slot of the cable-tube.

The object of my invention is, first, to provide 20 an improved construction of sprocket-wheel for connecting the car with the moving cable and improved means for lifting said sprocket-wheel in such manner that its arms shall be freed from engagement with the cable 25 and pass from out the slot of the cable tube, and, secondly, to provide improved means for controlling the revolution of the sprocket-wheel from the platforms of the car when the car is to be started or its movement is to be arrested. 30 To this end my invention consists in the various novel features of construction herein-after described, illustrated in the accompanying drawings, and particularly defined in the claims at the end of this specification.

35 Figure 1 is a view, partly in side elevation and partly in central vertical section, of a cable-railway car embodying my invention, the subjacent tube with its propelling cable being shown in proper position with respect to the 40 sprocket-wheel of the car. Fig. 2 is an enlarged detail view in vertical section on line $x-x$ of Fig. 3. Fig. 3 is a plan view of the sprocket-wheel and its connections, the body 45 of the car being removed. Fig. 4 is a detail view in cross-section of the sprocket-wheel.

A designates the main body of the car, of which A' and A'' are the platforms, and B denotes the journal-box frame, of usual or suitable construction.

50 Beneath the journal-box frame B are held, by means of the usual spring-carrying rods,

B', the side bars, C, the inner ends of which are bent into angular shape, as shown at c , and sustain the cross-bars C', which extend between the side bars, C, on each side of the car. Between the cross-bars C', and suitably bolted thereto, extend the journal-bearing bars D, and from the center of these bars rise the journal-brackets d, the bases of which are suitably bolted to the bars.

Within the brackets d are held, in a manner permitting their movement in upward direction, the journal-boxes E, which serve to sustain the ends of the axle E', whereon is placed the sprocket-wheel F. The body of this sprocket-wheel F is provided with a series of projecting arms, f, of substantially the shape illustrated in the drawings, and formed at equal distances around the periphery of the wheel, the outer and larger portion of these arms being provided with flat faces f' , adapted to engage with the correspondingly flat faces of the stops W of the propelling-cable. My purpose in thus forming the arms f with the expanded ends having flat faces f' is to insure 70 a better bearing of the ends of these arms against the faces of the stops W of the cable, and each arm f of the sprocket-wheel is provided with two flat faces f' , so that the sprocket-wheel will be properly caught by the stops 75 of the cable when the car is moving in either direction. It will be readily understood, however, that with cars designed to move in one direction only the arms of the sprocket-wheel need have but one of the faces f' .

It will be observed that the body of the friction-hub F' is formed with the annular space f'' therein, to lessen its weight, and from this space and through the sprocket-wheel pass the bolts f''' , which serve to unite the 90 sprocket-wheel and friction-hub, as shown in Fig. 4. The outer portions of the axles E' pass through suitable perforations in the ends of the arms G, the inner ends of these arms being journaled upon the bar g, sustained by 95 the brackets g', that are bolted to and rise from the journal-bars D of the sprocket-wheel frame. To the side of the sprocket-wheel F is bolted the friction-hub F', over which passes the friction-strap F'', which serves to control 100 the movement of the sprocket-wheel, as will presently appear, and on the axle E', on either

side of the sprocket-wheel F, are placed the coil-springs H, which serve to sustain said sprocket-wheel in a normally central position and yet permit this wheel to be moved in 5 lateral direction to compensate for the slight lateral movement of the car or any irregularities in the slot of the cable-tube. Upon the axle E' is fitted the collar E², the ends of which bear respectively against the arm G 10 and the coiled spring H.

The journal-boxes E are provided with the flanges e, to secure their accurate movement within the journal-brackets d, and it will be observed that the bearing-faces of these brackets d are struck on the segment of a circle, the center of which is the bar g, whereby the arms G are carried, the purpose in thus forming the journal-brackets being to allow the journal-boxes to rise freely in vertical direction 15 when the sprocket-wheel is to be lifted from out the slot of the cable-tube, as will be hereinafter set forth; and it will be observed that the arms G, swinging upon the bar g as a center, can carry the journal-boxes and the parts 20 sustained thereby in upward direction, such boxes being guided during this movement by the grooved faces of the journal-brackets.

To the bar g or other suitable fixed point is attached, by means of the chain i, one end of 30 the friction-strap F², which passes around the friction-hub F', the opposite end of this strap being connected to a suitable chain, i, that passes beneath the guide-pulley K, that is journaled upon the cross-bar k and above the guide-pulley 35 K', sustained by the bracket k', and is fastened to the main lever L, that is pivotally sustained within the bracket l, depending from one of the sills of the car-frame. To the outer ends of the lever L are connected, respectively, the rods M 40 and N, which lead to the winding-posts at the opposite ends of the car, the outer ends of these rods M and N being provided with suitable chains, n, which pass around the lower end of the winding-post. The lower portions of the 45 winding-posts O are also provided with the usual rods and chains, P and P', that connect with cross-levers of usual construction, which are united with the brake-beams by the chains p, and serve to set the brake-shoes against 50 the tread of the car-wheels.

It will be seen that the chains n are wound upon the ends of the winding-posts O in reverse direction to the chains P', the purpose of this arrangement being to cause the brake-shoes 55 of the car to be set when the car is disconnected from the running cable and to cause the brake-shoes to be thrown off the wheels when the car is to be moved by the cable.

It will be seen from the construction as 60 thus far defined that if either of the winding-posts O is turned in such manner as to tighten the friction-strap F² against the surface of the friction-hub F' the movement of the sprocket-wheel F would be gradually arrested and the 65 arms of the sprocket-wheel will be caught by the buttons W upon the constantly-traveling cable W' in such manner as to gradually move

the car forward, and at the same time the chains P will be unwound, so as to permit the brake-shoes to swing from off the running 70 wheels. By connecting the friction-strap with the winding-posts at the opposite ends of the car through the medium of the cross-lever L I am enabled to readily arrest the movement 75 of the sprocket-wheel from either platform of the car.

In order to permit the sprocket-wheel to be lifted from the cable-tube, either for the purpose of allowing this wheel to pass over obstructions in the roadway—such as cross-tracks or the like—or when for any reason the car is to be drawn by horses, I have provided the improved mechanism for lifting the sprocket-wheel from out the slot of the cable-tube. Upon the cross-bar g is held one end 80 of the lifting-arm R, the opposite end of such arm passing beneath the axle E', and being slightly upturned and connected by a suitable pivot pin or bolt to the link R', which in turn is pivotally connected to the inner ends of the 85 levers S and S', extending from the center of the car to a point beneath its platforms. The levers S and S' are pivoted about their centers to the plates s, depending from the body of the car, and the outer ends of these levers are 90 provided each with a step-rod, T, the upper enlarged portion, t, of which extends in convenient position to be depressed by the foot of the driver. In each of the step-rods T are formed the upper and lower notches, t' and t'', 95 with which engage the pawls V, that serve to sustain the step-rods in elevated or depressed condition.

From the foregoing construction it will be seen that when it is desired to lift the sprocket-wheel in order to permit such wheel to pass over an obstruction, or for any other purpose, it is only necessary for the driver to depress the step-rod T or T' until this rod is brought in such position that the pawl V can engage 105 with its upper notch, t', which will serve to hold the step-rod depressed and the sprocket-wheel in elevated position.

By my improved mechanism the sprocket-wheel can be readily lifted by the driver from 110 his position on the platform of the car, and all necessity for providing the car-floor with a trap-door for this purpose is avoided. It will be seen that by extending the lifting-arm beneath the axle of the sprocket-wheel this 115 arm is allowed a freedom of movement to compensate for the vertical movement of the car-body upon its springs; hence I am enabled to provide the sprocket-wheel with a means for lifting the same, which, while connected with 120 the body of the car, does not impart the movement of the car in anywise to the sprocket-wheel.

Having thus described my invention, what I 125 claim as new, and desire to secure by Letters Patent, is—

1. In a cable-railway car, the combination, with a vertically-movable sprocket-wheel and its friction-drum located between the axles of

- the car, of a friction-strap for said drum, a cross-lever, L, a flexible connection extending from one end of said strap to said cross-lever, suitable guides for said flexible connection, 5 and suitable connections extending from said cross-lever to the ends of the car, substantially as described.
2. In a cable-railway car, a sprocket-wheel having arms f, provided with expanded ends 10 f', having one or more flat faces adapted to engage with the stops of a traveling cable, substantially as described.
3. In a cable-railway car, a sprocket-wheel composed of a body, F, having arms f formed 15 integral therewith and having a chambered friction-hub, F', bolted thereto, substantially as described.
4. In a cable railway car, the combination, with the sprocket-wheel and its axle, of lifting 20 mechanism for such sprocket-wheel extending to the platform of the car, substantially as described.
5. In a cable-railway car, the combination, with the sprocket-wheel, its axle, and suitable 25 fixed journal-bearings for such axle, of a swing-
- ing lifting-arm for said sprocket-wheel, and suitable connections extending from said arm to the platforms of the car, substantially as described.
6. In a cable-railway car, the combination, 30 with the sprocket-wheel and its axle, of a pivoted arm or arms connected with said axle, and curved journal-bearing brackets for such axle, substantially as described.
7. In a cable-railway car, the combination, 35 with the sprocket-wheel and its axle, of coiled springs mounted upon said axle at the side of the sprocket-wheel, substantially as described.
8. In a cable-railway car, the combination, 40 with the sprocket-wheel and its axle, of lifting mechanism for said sprocket wheel, comprising a pivoted arm extending beneath the axle and one or more pivoted levers to which said swinging arm is connected, said pivoted levers extending to the end or ends of the car, substan- 45 tially as described.
